UNITED STATES PATENT OFFICE.

SAMUEL S. SIGEL, OF PORTLAND, AND AXEL W. JOHNSON, OF LENTS, OREGON.

WINDOW-CLEANING DEVICE.

1,108,258.

Specification of Letters-Patent. Patented Aug. 25, 1914.

Application filed March 13, 1913. Serial No. 754,162.

To all whom it may concern:

Be it known that we, SAMUEL S. SIGEL, of Portland, and AXEL W. JOHNSON, of Lents, in the county of Multnomah and State of Oregon, citizens of the United States, have invented certain new and useful Improvements in Window-Cleaning Devices, of which the following is a specification.

Our invention relates to improved means for cleaning windows, and has particular reference to a device for cleaning the look-out window of motor propelled vehicles. The operator of vehicles of this class is often seriously annoyed by rain or snow settling on the look-out window of the vehicle, to such an extent, indeed, that he usually in inclement weather is compelled to lower said window in order to obtain a clear view ahead, whereby he exposes himself dangerously. This condition pertains on the cars of street railways and other railways and also on motor propelled vehicles of the automobile type using a wind shield.

The object of our invention is to provide efficient means for cleaning such windows by a simple and convenient hand operation not necessitating an interruption of the operator's duties.

To this end our invention consists in the combinations and advantageous features hereinafter fully explained and illustrated in the accompanying drawings, of which:

Figure 1 is an elevation of a device embodying our invention, Fig. 2 is a modified form of Fig. 1 reduced, showing that the device may be attached to each end of the sash, Fig. 3 is a cross-sectional elevation substantially through the center of the vertical portion of the device, and disclosing the upper portion of the device, Fig. 4 in a similar manner discloses the lower portion, and Fig. 5 is a modification of Fig. 3.

On the sash-frame 1 is detachably mounted a vertically disposed tube 2 by means of suitable clamps 3. Said tube terminates at the top in a hollow head 4, from which extends a horizontal tube 5. In the tube 5 is rotatably fixed a spindle 6, and an encompassing coil-spring 7 is suspended between the spindle and the wall of the tubing, very much in the manner the spring is hung on the spindle of a shade roller. The outer end of said spindle is centrally located in the head 4, and a suitable strap 8 is wound around the spindle. The inner end of the strap is fixed and its outer free end is at-

tached to a tubular slide 9, said slide mounted to operate in the vertical tube 2. A suitable cord 10 extends from said slide downwardly over a pulley 11 and through a perforation of the sash frame, and said cord terminates in a handle 12. By pulling on said handle the slide 9 is caused to move downward in the tube 2 against the tension of the spring 7, which, when the handle is again released, returns the slide to its upper position.

A rod 14, carrying a pawl 13, is rotatably hung in the slide 9, and the said rod extends horizontally through a slot 15, said slot extending vertically the length of the tubes. This rod 14 is fitted with an extension tube 16, and fixed studs 17 are provided for attaching a cleaning bar 18 made with a rubber insert 19, as commonly used for the purpose of cleaning window panes. The extension means is provided for the purpose of fitting cleaning bars of various lengths, and suitable clamping means 20 serve to securely clamp the extension 16 on the rod 14, when properly set.

The function of the pawl 13 is to position the cleaning bar, as will now be described. The rotary movement of the pawl is limited by suitable means, such as shoulder-portions 21 of the pawl engaging a fixed stud 22 of the slide. The apex 23 of the pawl lodges in a perforation 24 of the slide. Let it now be assumed that the operator of the vehicle wishes to clean the window, and that the mechanism is positioned as shown in Fig. 3. He grasps the handle 12 of the cord 10 and pulls said handle toward him, thereby drawing the slide 9 downward, as already described. It is noticed that the apex 23 of the pawl projects over the end of a resilient finger 25, and the pawl is by this finger caused, in moving downward, to turn to the angular position shown in Fig. 4, in which it remains until its bottom position, as shown in said Fig. 4, is reached. It is readily understood, by referring to the Figs. 3 and 4, how the insert 19 of the cleaning bar 18 passes over the glass 26 of the sash during this downward movement.

It is noticed that the apex of the pawl 13 takes a position in front of a second resilient finger 27 (in Fig. 4) and this finger serves to throw the pawl, and in turn the cleaning bar, to its initial position when the slide 9 is retracted by the spring 7. The fingers 25, 27 are made resilient in order to permit the

pawl to pass on its forward movement, relative to the finger operating, but said fingers are made stiff enough to throw the pawl on its return movement without thereby being bent. A convenient backing for the fingers is provided by beveling the edges of the perforation 24 of the slide, substantially as indicated at 28.

Fig. 5 is added in order to show how a handle 29 may be mounted directly on the slide, when convenient, thereby eliminating the cord 10 and the pulley mechanism 11. In Fig. 2 is shown a double construction, which differs from the above only in the manner of fastening the cleaning bar 32 on the rods 14 of the mechanisms, which in this case are made right and left, by means of a modified extension tube 33. Pulleys 34, 35 are provided for the purpose of guiding both pulling cords to the operating handle 36.

The cleaning device herein described is readily operated by the person operating the vehicle, and he does not have to stop the vehicle or otherwise interfere with its running. It is also seen that the cleaning bar operates on the down-stroke, pulling the rubber insert over the glass pane, and that on returning the said bar swings entirely out of the way of said glass, thereby releasing the mechanism, which then readily is retracted by the spring, as described. The means of attaching the device to the window sash may, of course, be varied to suit conditions, or, if the sash is hollow, the device may be built right into the sash.

We claim:

1. In a device of the character described, a tubular frame comprising a vertical portion and a horizontal portion, a slide mounted to move in said vertical portion, a horizontal cleaning frame rotatably fixed in said

slide, a spring-held spindle in said horizontal portion and connected to draw said slide upward, manual means for drawing the slide downward, and resilient fingers on said vertical portion coöperating with said cleaning frame for the purpose of directing the frame relative to the glass.

2. In a device of the character described, a horizontal support to be mounted on a sash frame, means for yieldingly retaining the support at the top of said frame, means for drawing said support downwardly, a detachable cleaning bar on said support, means on the support to longitudinally adjust the cleaning bar and means to press the cleaning bar against the adjacent window glass on the down stroke and away from said glass on the up stroke.

3. In a device of the character described, a vertical tube, a slide movable in said tube, a horizontal rod fixed to oscillate in said slide, and extending through a slot the length of the tube, a pawl on said rod within said slide and presenting its apex toward an opening in the slide, resilient fingers fixed at the top and bottom of the tube, a cleaning frame detachably fixed on said rod, means for drawing said slide downward through the tube, a retracting spring for returning the slide, the said fingers operating on reversing the movement of the slide to shift the said cleaning frame against the adjacent window pane on the downstroke and away from the pane on the upstroke.

In testimony whereof, we have hereunto affixed our signatures.

SAMUEL S. SIGEL.
AXEL W. JOHNSON.
